UNITED STATES PATENT OFFICE.

ADRIAN HALL AND JOHN M. HALL, OF GREENFIELD, INDIANA.

CONVEYING APPARATUS.

No. 802,857.

Specification of Letters Patent.

Patented Oct. 24, 1905.

Application filed June 12, 1905. Serial No. 264,838.

To all whom it may concern:

Be it known that we, ADRIAN HALL and JOHN M. HALL, of Greenfield, county of Hancock, and State of Indiana, have invented a certain new and useful Conveying Apparatus; and we do hereby declare that the following is a full, clear, and exact description thereof, reference being had to the accompanying drawings, in which like numerals refer to like parts.

The object of this invention is to operate successfully and practically a cable apparatus for conveying material from one point to another. It is especially adapted for loading and unloading steamboats at landings and for excavating ditches, trenches, sewers, and the like.

One feature of the invention consists in providing novel means for operating an endless cable to move a carrier back and forth on a stationary supporting-cable, said means consisting herein of a drum driven by a wheel having an internal periphery and a hub opposing each other and a driving-pulley movable into engagement with said hub and internal periphery for driving the drum in one direction or the opposite, as desired, and thus moving the carrier as desired.

Another feature of the invention consists in combining with the driving means a drum for tightening the supporting-cable and in connection therewith means for holding the same in a taut condition.

The full nature of the invention will be understood from the accompanying drawings and the following description and claims.

In the drawings, Figure 1 is a perspective view of the device in operative connection with cables and supports to illustrate its use. Fig. 2 is a plan view of the operating device with the upper portion of one wheel cut away and parts arranged to move the carrier in one direction. Fig. 3 is the same as the right-hand half of Fig. 2 with parts arranged to move the carrier in an opposite direction. Fig. 4 is the same as Fig. 3 with the lower-drum-driving wheel idle. Fig. 5 is a vertical section through the eccentric-bearing and part of the frame. Fig. 6 is a plan view of the left-hand half of the device with parts arranged to tighten the cable. Fig. 7 is a side elevation of the ratchet with the rim of the gear removed. Fig. 8 is a detail of the brake, and Fig. 9 is a detail of the ball-bearing on the shaft.

In detail, the operating mechanism is mounted upon a frame having a rectangular base 10,

rear uprights 11, and inclined side pieces 12. In the upper part of the frame a drum 13 is mounted, on which a supporting-cable 14 is wound. This cable passes over a pair of forks 15 and is secured at the other end to a dead man 16. The purpose of this upper drum 13 is to tighten said cable 14, for said cable carries a pulley 17, that supports the carrier 18, by which the material, such as bales of cotton 60 or gravel or soil, may be conveyed. The carrier of course is to be modified to suit the material that is to be transported. The upper-drum shaft 19 has secured upon it a gear-wheel 20, whereby said drum is actuated. Said gear 20 has on its inner side the ratchet-teeth 21, that are engaged by a pawl 22 on a lever 23, extending out in front of the machine, whereby said pawl may be moved into or out of engagement with said ratchet for 70 holding said gear and the upper drum stationary when the supporting-cable 14 has been made taut. Said upper drum and gear are rotated by a pinion 24 on the shaft 25, that carries the sprocket-wheel 26, which is driven 75 from any suitable source of power by a sprocket-chain 27 continuously in one direction. Said pinion 24 is mounted loosely on the shaft and is put in connection with said shaft by a sliding clutch 28, which is operated by an arm 29, that is slidable in the guides 30, secured on the inclined side piece 12 at the left-hand side of the frame. Said arm is moved by the lever 31 and the connecting-bar 32, arranged as shown.

The lower drum 33 is mounted on the shaft 34, to which the lower-drum-driving gear 35 is secured. This driving-gear has a hub 36, toothed like a gear-wheel, and also an internally-toothed rim 37 on the side next to the frame. An endless cable 38 is coiled about the lower drum 33 and is connected with the carrier 18 and runs over a pulley at the remote end of the supporting-cable. The carrier is moved along on the supporting-cable by 80 the endless cable 38, operating alternately in one direction or the other, as may be desired.

The actuation of the lower drum in the one direction or the other is effected by a pinion 40, mounted on the right-hand end of the shaft 25 and movable into engagement with the toothed hub 36 of the driving-gear 35 or into engagement with the internally-toothed rim 37 of said gear or into an intermediate position out of touch with either 85 said hub or rim, so that the gear 35 would run idly, while the carrier might move by 90

gravity along the supporting-cable 14. In order that the pinion 40 may be moved into or out of engagement with the hub or the rim of said driving-gear 35, the shaft 25 is mounted in the eccentric 41, and said eccentric is oscillated by an arm 42, a connecting-rod 43, and a hand-lever 44. The other end of the shaft 25 must also be mounted in a slightly-movable bearing, and this is accomplished by mounting it loosely in the ball 45 and mounting the ball loosely in the bearing-cup 46, secured in the inclined side piece 12 at the left of the frame. The change of position of the lever 34 is not very great—at least not sufficiently great to interfere with the operation of the gear-wheels.

This makes a convenient and simple apparatus for moving the load-carrier and for tightening the supporting-cable. When used in connection with a steamboat, the frame is mounted on the deck of the boat, and the cable is run out and secured upon the landing. After the supporting-cable is made taut by the machine the gear 20 is thrown out of operation by the lever 33 and then the machine runs continuously, moving the carrier in one direction or the other at the will of the operator in charge of the hand-lever 44. If the carrier needs to be stationary while loading or unloading, he throws the pinion 40 into its inoperative position between the hub and the rim of the gear 35. This avoids the need of a clutch mechanism for accomplishing said result.

35 For the purpose of quickly stopping the machine a brake mechanism is provided, consisting of a pedal 50, fulcrumed at 51 to the frame, as shown in Fig. 8, and carrying a brake-shoe 52, adapted to bear against the periphery of the wheel 35.

What we claim as our invention, and desire to secure by Letters Patent, is—

1. In a conveying apparatus, the combination of a carrier, an endless cable for moving said carrier, a drum for operating said cable, a gear-wheel that actuates said drum, said gear-wheel being provided with an internal and an external series of gear-teeth, a pinion for engaging said gear-teeth, and means for moving said pinion into and out of operation with either series of gear-teeth.

2. In a conveying apparatus, the combination of a carrier, an endless cable for moving said carrier, a drum for operating said cable, a gear-wheel that actuates said drum, said gear-wheel being provided with an internal and an external series of gear-teeth, a pinion for engaging said gear-teeth, a frame, a continuously-operating driving-shaft on which said pinion is secured, an eccentric bearing oscillatory in said frame and in which the end of said shaft adjacent said pinion is mounted, and means for oscillating said eccentric bear-

ing so as to move said pinion into or out of engagement with either series of teeth on said gear-wheel.

3. In a conveying apparatus, the combination of a carrier, an endless cable for moving said carrier, a drum for operating said cable, a gear-wheel that actuates said drum, said gear-wheel being provided with an internal and an external series of gear-teeth, a pinion for engaging said gear-teeth, a frame, a continuously-operating driving-shaft on which said pinion is secured, an eccentric bearing oscillatory in said frame and in which the end of said shaft adjacent said pinion is mounted, means for oscillating said eccentric bearing so as to move said pinion into or out of engagement with either series of teeth on said gear-wheel, and a ball-bearing in said frame for mounting the other end of said shaft to permit the oscillation of said eccentric bearing.

4. In a conveying apparatus, a stationary supporting-cable, a frame at one end of said cable, means mounted on said frame for tightening and holding said cable taut, a carrier movable on said stationary cable, an endless cable for moving said carrier, and means mounted in connection with said frame for moving said endless cable in opposite directions.

5. In a conveying apparatus, the combination of a carrier, an endless cable for moving said carrier, a drum for operating said cable, a gear-wheel that actuates said drum, said gear-wheel being provided with an internal and an external series of gear-teeth, a pinion for engaging said gear-teeth, a frame, a continuously-operating driving-shaft on which said pinion is secured, an eccentric bearing oscillatory in said frame and in which the end of said shaft adjacent said pinion is mounted, means for oscillating said eccentric bearing so as to move said pinion into or out of engagement with either series of teeth on said gear-wheel, a supporting-cable on which said carrier moves, a drum mounted in said frame to which one end of said cable is secured for tightening and holding the same, a gear for actuating said tightening-drum, a pinion loosely mounted on said shaft for operating said gear, means for clutching said pinion into operative engagement with said shaft, a ratchet secured to the gear that actuates said tightening-drum, and a lever-controlled pawl for engaging said ratchet.

In witness whereof we have hereunto affixed our signatures in the presence of the witnesses herein named.
